TYPEWRITING MACHINE

Henry L. Pitman, Westfield, N. J., assignor to
Underwood Elliott Fisher Company, New York,
N. Y., a corporation of Delaware

Application January 7, 1933, Serial No. 650,629

14 Claims. (Cl. 197—66)

This invention relates to a motor-driven typing-machine carriage, and particularly to a carriage-return mechanism in which an electric driving motor is normally silent, the motor being energized concurrently with the operation of a key-controlled clutch to connect the carriage to transmission mechanism operative by the motor.

The motor, started from rest at the beginning of each carriage-return operation, must be enabled to exercise a sufficiently strong torque upon the transmission mechanism in order to overcome with reasonable celerity the inertia of the carriage and other parts.

It has been found that a motor capable of starting the carriage off with the desired degree of celerity has a tendency, noticeable particularly in an extended run, to continue to speed up the carriage. It is difficult to impart to the carriage a reasonably fast, yet smooth and even return movement, irrespective of the extent of such return movement and undefeated by the accelerating characteristic of the motor.

It is contrived by this invention to provide a governing device responsive to the speed of the carriage movement, and operative, in the preferred embodiment of the invention, to regulate a friction-coupling device which connects the motor and transmission mechanism. There is shown a reciprocating-carriage starting device which enables the motor, started from rest, to rapidly start the carriage for a short run. Such starting device is self-adjusting as a torque-transmitter, and it therefore transmits the requisite strong carriage-starting torque from the motor as soon as the latter is started, but diminishes the torque transmission in proportion to the tendency of the continuing strong motor torque to overspeed the carriage, in long carriage-return runs. With the use of such carriage-starting device, when practicing the desired speed of carriage-return movement, the momentum of the carriage, when it approaches the usual carriage-arresting stop, will be substantially uniform for long, short, and intermediate carriage-return runs. The impact of the carriage against said stop may therefore be minimized to a degree heretofore unattainable. This is because it is obviously easier to control the impact arising from a uniform momentum, than an impact which arises from the heretofore variable momentum, it being understood that there is the usual unvariably timed disconnection of the motor just before the carriage reaches the stop. A feature of the invention resides in combining the friction coupling and governing

devices in a simple and compact, unitary assembly. This assembly is preferably at the juncture of the motor-shaft and a transmission shaft, the two shafts being substantially in axial alignment. The motor-shaft presents a friction-clutch facing preferably in the form of an outer peripheral surface. Said surface may be frictionally engaged by a spring-pressed shoe or shoes connected to and rotatable with the other shaft. These shoes may be arranged so as to be subject to centrifugal action tending to displace the shoes away from said surface. The centrifugal action may be controlled by the counteraction of the shoe-pressing springs in such manner that the frictional coupling between the shoes and said peripheral surface tends to weaken as the speed of the transmission shaft and hence of the carriage tends to increase beyond a predetermined limit. Such increase in speed is therefore automatically checked by slippage in the frictional coupling resulting from the weakening of the latter.

Means are provided to finely adjust the pressure of the shoes upon the co-operative peripheral surface and thereby not only regulate the speed of the carriage-return movement to the desired maximum, but also assure that the friction coupling shall transmit the requisite torque to overcome the inertia at the beginning of a carriage-return run. The invention enables the motor to impart to the carriage a smooth, even movement which is in pleasing contrast to the sustained acceleration of movement heretofore obtaining and which sustained acceleration was deleterious to the life of the mechanism.

The shoes may be in the form of arms pivoted to a spider or disk fastened to the transmission shaft, the free ends of the arms being weighted for centrifugal action. The free ends of the arms may be faced with friction material shaped to bear upon the peripheral surface presented by the motor-shaft. Said peripheral surface may moreover be spherical so that the coupling serves as a universal joint between the two shafts which such coupling connects. For readily establishing the necessary intersection of the two shaft-axes according to the practice obtaining in universal joints, the coupled ends of the shafts are articulated with one another by means of a simple ball-and-socket contact. The ball may be formed at the end of the transmission shaft and has its center substantially coinciding with the center of sphericity of the clutch-facing. The socket may be in the form of a central hole in a member fas-

tened to the motor-shaft and upon which said spherical periphery is shaped.

A circular shell forms with the aforesaid spider or disk an enclosure within which the coupling-device, including the aforesaid weighted arms on said disk, is housed. Each of said arms is provided with a spring operative to press the shoe-part of the arm upon the aforesaid peripheral surface. Each spring is connected to the shell so that a rotative displacement of said shell will serve to vary the pressure of the several springs upon their respective arms. The shell may be secured or fastened in any position within its range of adjustment.

15 Other features and advantages will hereinafter appear.

In the accompanying drawing,

Figure 1 is a view taken from the rear of the typewriter showing the transmission mechanism, 20 motor, and the novel coupling device.

Figure 2 is a cross-sectional view through the shell surrounding the coupling-device and through the motor-shaft showing details of the shoe forming arms and the springs associated 25 therewith.

Figure 3 is a skeleton perspective view showing the motor, part of the typewriter-carriage and carriage-return control, the transmission mechanism and the novel coupling-device.

30 Figure 4 is an enlarged view of the coupling-device in perspective, some of the parts being shown broken away and sectioned to bring out structural details.

35 Figures 1 and 3 indicate carriage-return mechanism of the character shown in my Patent No. 1,580,326, dated April 13, 1926. The typewriter indicated herein is the well-known Underwood and includes a machine-frame 10, supporting a carriage-frame 11, movable in letter-feed and 40 return directions on front and rear rails, the rear rail 12 being shown in Figure 1.

A carriage-return key-lever 13 is operative to raise the forward end of a link 14 to release the same from fixed holding plate 15. The released 45 link is drawn rearwardly by a spring 16 to rock a shaft 17, and thereby slide a carriage-returning pinion 18 rearwardly, the pinion being articulated with a partly-shown shift arm 19 operatively connected to the rock-shaft 17. The carriage-returning pinion 18 has clutch-teeth 20, which, when said pinion is shifted rearwardly, engage a clutch-member 21, keyed to a shaft 22, on which the pinion 18 is slidably mounted. The 50 rock-shaft 17 is connected to the rear end of the releasable link 14 by an arm 14* fastened to said shaft. Another arm 23, fastened to said rock-shaft 17, enables the latter to operate a switch-arm 24 closable upon a fixed contact 25, the switch-arm 24 and the arm 23 being connected by 55 the usual link 26.

Closing of the switch-arm 24 upon the contact 25 connects a normally silent electric driving motor 27 to a source of current-supply represented by leads 28. The rearward shift of the 60 carriage-returning pinion 18 into engagement with the clutch-member 21 is thus attended by energization of the normally silent electric motor whereupon the pinion 18 is rotated by said clutch-member 21 to drive the typewriter-carriage frame 11 in a carriage-return direction through the medium of a rack 29 mounted on said carriage on the usual brackets 30.

The usual speed-reducing gearing, generally indicated by the reference number 31, is provided 75 between the carriage-returning pinion and the

motor 27. Said reduction gearing includes a worm-wheel 32 fastened to the shaft 22 and driven by a worm 33, keyed to a shaft 34. A motor-shaft 35 has a floating extension 36 connected thereto by a suitable universal joint 37. The motor-shaft extension 36 has its free end in endwise abutment with the end of the worm-shaft 34, said worm-shaft end projecting beyond the usual housing 38, within which the reduction gearing is retained.

10 The novel coupling and speed-controlling means, generally indicated by the reference number 39, serve to couple the motor-shaft extension 36 to the worm-wheel shaft 34 and will be presently described.

15 The carriage-return rack 29 is mounted upon its supporting brackets 30, so that it is capable of the usual limited endwise movement relative to the carriage-frame 11. Said endwise movement of the rack 29 is utilized for line-spacing a 20 platen 40, mounted on an axle 41, journaled in a platen-frame 42, supported by the carriage-frame 11. The carriage-return rack has the usual teeth 43 enabling it in said endwise movement to operate a train 44 which includes an upper arm 45 capable of imparting to the usual line-space slide 46 a rearward line-spacing stroke. Said slide carries the usual line-space pawl 47 which is co-operative with a toothed line-space wheel 48, fastened to the platen-axle. The line-spacing train 44 is substantially as set forth in Patent No. 1,835,776, to W. F. Helmond, dated December 8, 1931, and is supported on a bracket 50, fastened to the carriage-frame 11. For guidance in its endwise line-spacing movement the 30 carriage-return rack 29 is provided with slots 51 fitting over rearwardly-extending arms 52 of the supporting brackets 30. Movement of the rack 29 relative to the carriage-frame 11 is limited by the striking of the ends of the slot 51 40 against the side edges of the bracket-arm 52. A spring 54 co-operates to restore the rack and line-space parts to the normal positions seen in Figure 3.

Upon operation of the carriage-return key-lever, the initial portion of the resulting rightward movement of the rack 29 is thus effective 45 to line-space the platen 40, and when the left end of the rack-slot 51 encounters the side edge of the bracket-arm 52, the entire carriage starts on its rightward or return movement. Said rightward movement of the carriage is automatically terminated by the usual means to rock the shaft 17 contrariwise to shift the pinion 18 forwardly to withdraw its teeth from the clutch-member 21, 50 and also to withdraw the switch-arm 24 from the fixed contact 25 to silence the motor 27. The contrariwise rocking of the shaft 17 is also effective to relatch the link 14 over the holding plate 15. Said return-run-terminating means 55 are fully set forth in my said Patent 1,580,326 and in Patent 1,238,908 to F. A. Hart, dated September 4, 1917. Briefly described, said means include, see Figure 3, a dog 93* splined to a shaft 94 and coupled to the usual right-hand margin-stop 95* for lateral adjustment with the latter. Said dog, when struck by a carriage-tappet 96* just before the carriage is arrested by said stop 95*, rocks said shaft 94, which, in turn, rocks said shaft 17 through linkage 97 for said disconnection of the carriage and motor.

Heretofore the electric motor 27, starting from rest at each carriage-return operation, returned the carriage at varying rates of speed, depending upon the extent of the carriage-return run 75

and the degree of momentum acquired by the carriage. In an extended run the speed was liable to become unduly accelerated as the carriage and driving parts gained in momentum, and the carriage would be projected with undue force against the stop which limits the carriage-return.

To overcome this difficulty, the novel coupling-means 39, now to be described, are provided. The motor-shaft extension 36 has fastened thereto a part 55, in which the extension 36 is inserted to a limited depth as indicated in Figures 1 and 4. This leaves at the free end of said part 55 a central hole, the bottom of which is formed by an end 56 of the motor-shaft extension 36. Abutting said end 56 is a ball 57 formed on the end of the worm-shaft 34 and fitting the central hole of the part 55. Said part 55 has a flange 53, the outer periphery of which is shaped, see Figures 1 and 4, to form a spherical friction-clutch facing 59. The part 55 is so set on the motor-shaft extension 36 that the center of the clutch-facing sphericity coincides with the center of the ball 57. A set screw 58 secures said part 55 to the motor-shaft extension 36.

A spider or disk 61 has a hub 62, whereby said disk is fastened to the worm-shaft 34 by a set-screw 63. The outer face of the disk 61 is near the end of the part 55 as in Figure 1, and serves to carry arms 65, shaped to closely surround the clutch-facing 59 as seen in Figure 2. Each arm 65 is recessed as at 64, Figures 2 and 4, to receive and retain a shoe 66, made of friction material and shaped to fully bear upon the spherical clutch-facing 59. Each arm 65 is pivoted upon a stud 68 projecting from the face of the disk 61.

The studs 68 project slightly beyond the arms 65 to support a shell 70, having a turned rim 71 which clears the arms 65 and which may overlap the edge of the arm-supporting disk 61. The shell 70 and the disk 61 thus form an enclosure within which the novel coupling is contained. Said shell also forms an abutment for a compression spring 72 with which each of the shoe-arms 65 is provided for the purpose of causing its shoe 66 to be pressed upon the spherical clutch-facing 59. The rim 71 of the shell 70 has accordingly punched inwardly therefrom tongues 73 upon which the springs 72 are set and retained. The other end of each spring 72 is received in a recess 74 formed in the outer end of the arm which has a jog 75 to clear said spring 72 as seen in Figure 2. The shell 70 also affords readily accessible means for adjusting the pressure of the springs 72, and, to this end, the shell is fastened to the supporting studs 68 by screws 76 threaded into the ends of said studs 68 and passing through slots 78 formed in the shell so that the latter may be capable, when the screws 76 are loosened, of rotative displacement, effective to more or less compress the springs 72, and thereby adjust their pressure. The shell 70 has a central opening clearing the hub-portion of the clutch-facing part 55.

The electric motor 27 is fastened by screws 78 to a bracket 79 which is fastened to the back of the typewriter-frame 10 by screws 80. The reduction-gearing housing 38 has a flange 81, whereby it is fastened to the back of the typewriter-frame by screws 82. For the purpose of providing for up-and-down adjustment of the housing 38 to mesh the carriage-returning pinion 18 properly with the teeth of the carriage-returning rack 29, one of the screws 82 passes through a vertical slot 83 in the housing-flange 81. The other screw is surrounded by an eccentric bush-

ing 84 fitting a hole in said flange 81, and so positioned that by turning said bushing 84, the housing may be adjusted up and down, the vertical slot 83 permitting this up-and-down adjustment. The screws 82 are tightened when the adjustment has been effected.

For supporting the rack 29 against upward thrust, a finger 86, Figure 3, abuts the upper edge of the rack 29 and is carried by the housing 38. To compensate for the up-and-down adjustment 10 of said housing, said finger 86 is also made adjustable on said housing, and, to this end, is formed as seen in Figure 3, so that it may be secured by screws 87. One of said screws passes through an eccentric bushing 88 which may be 15 so positioned that turning of the bushing will swing the finger 86 up or down, the finger swinging about the other screw 89.

The parts constituting the electric switch for the motor may be contained within a hooded portion 90 formed integral with the motor-supporting bracket 79 as seen in Figure 3. An insulating plate 90 is supported by studs 91 secured to the rear wall of the hood by screws 92. Said studs present the insulating plate 90 so that the switch-members 24, 25, mounted thereon, are in the positions seen in Figure 3.

One of the leads 93 coming from the motor is directly connected to one of the leads 28. The other lead 93 is connected to the switch-arm 24, 30 and the other lead 28 is connected to a conductor-plate 95 bearing the switch-contact 25 and fastened to the insulating plate 90 by means of the stud 91 and an insulating bushing 96. The insulating plate 90 has a slot 97 within which the rear end of the switch-link 26 is slidably supported.

The novel clutch and speed controller is operative as follows. The springs 72 press the shoes 66 against the spherical clutch-facing 59 with 40 such force that when the carriage-return key-lever 13 is operated, the frictional connection between the shoe 66 and the clutch-facing 59 is effective to transmit the motor-torque to drive the rack 29 for the line-spacing movement and 45 also for the start of the carriage-return movement. As the carriage gains in momentum the motor 27 will speed up, and as it so speeds up, the arms 65, weighted at their free ends by reason of their shape as indicated in Figure 2, 50 will tend to swing outwardly against the opposition of the arm-springs 72. This tends to weaken the friction coupling between the shoes 66 and the clutch-facing 59, and, at a predetermined speed of carriage movement, there will 55 be a certain slippage between said shoes and facing which is effective to prevent the carriage speed from exceeding a predetermined maximum. It will be understood that the springs 72 are proportioned for said maximum speed, and that, 60 moreover, their pressure may be adjusted by turning the shells 70, 71 one way or the other.

The novel coupling is thus effective to transmit from the motor to the worm-shaft 34 a strong torque at the beginning of the return operation, the transmission being determined by the pressure of the shoe-springs 72, which, at the beginning of the rotation of the parts, exert their full force upon the shoes 66. As the speed of the parts increases up to the point where the carriage is traveling at the desired maximum, the force of the spring 72 is partly overcome by the centrifugal action of the arms 65, and the desired maximum speed of the carriage can never be exceeded because any excess of speed is counter- 75

acted by increased centrifugal action of the arms 65, which, in turn, is effective to counteract the spring pressure to weaken the friction coupling, and thereby automatically check such increase.

5 Should the friction coupling tend to become weakened to the extent that the carriage speed tends to fall below its desired maximum the centrifugal action of the arms 65 will be reduced and correspondingly the friction coupling will be strengthened to maintain the carriage speed at said maximum. The carriage speed, after the carriage is fairly under way, that is, when it has attained its maximum speed, is kept uniform by the mutually balancing effect of the spring force and centrifugal action. Moreover, the carriage is quickly brought under way since the full starting torque of the motor may be transmitted by the improved coupling, the springs 72 exerting at the start of the carriage-return run substantially their full force as stated. The springs 72 may be proportioned and adjusted so that there is substantially no slippage in the coupling-means while the carriage, starting from rest, is attaining its said maximum speed.

25 I am aware of Patent 1,580,326, granted to me, in which is shown a standard Underwood type-writer-frame and a correspondence-size carriage especially equipped for typing small telephone bills; the width of the bill, Figures 1 and 4, being only a fraction of the width of the usual correspondence paper-carriage, and the typed line in the patent being perhaps no more than one-third or one-fourth of the length of the usual typed line in typewritten correspondence. Hence, 30 the carriage of the patent has nothing but short return runs. Therefore, the carriage-returning motor may be directly coupled to the carriage-returning train, and the coupling may transmit the full torque of the motor to the carriage-returning train at all runs.

40 Owing, however, to the fact that the return run of the carriage is short, there is no opportunity for such growing increase in momentum of a heavy carriage, as would cause damage at 45 the arrest of the carriage by the usual return stop.

In the present invention, it will be perceived that the carriage-returning electric motor may be normally idle, and the carriage-return train normally disconnected from said motor, and rapid short return movements of the carriage are limited by the stop. A normally-closed clutch connects the motor to the carriage-train, and key-operated means start the motor into action and 55 connect it to said train. Said clutch is effective to transmit the full driving force of said motor to start said carriage during short runs. Said train however has means to prevent excessive momentum of the carriage due to motor acceleration during a long run thereof. In this way, damage from arresting the carriage by said stop in a long run is prevented. This preventing means includes a powerful friction clutch between the motor and the carriage-driving gear, which is 60 sufficiently effective to maintain the full torque of the electric motor upon the carriage when starting and driving it for short runs. The clutch is releasable by centrifugal force during long runs, to prevent momentum of the carriage from being augmented beyond a predetermined maximum. Hence the blow delivered by the carriage against 65 said stop, in terminating a long stroke, is about equalized with the blow delivered at a short return stroke.

70 This invention presents the equivalent of a

positively coupled motor and carriage, whereby the latter is promptly started for short runs, with means to prevent excessive momentum of the carriage due to motor acceleration during a long run thereof, whereby damage from arresting the carriage by the stop at the end of a long run is prevented. A friction clutch transmits the full torque of the electric motor to the carriage for a short run, without lag between the carriage and the motor, the clutch being releasable by 10 centrifugal force during long runs to avoid excessive stop-damaging accumulation of momentum by the carriage. Hence, short return strokes may be made more rapidly, and with consequent increase in output of the machine, without incurring danger of injury to the stop from excessive momentum of the carriage on long runs.

15 By reason of the sphericity of the clutch-facing 59, the novel coupling-means 39 also acts as a universal joint and therefore the motor-shaft extension 36 need not be in exactly straight alignment with the worm-shaft 34. The floating motor-shaft extension 36 facilitates adjustment of the housing 38 up or down for securing the proper meshing of the pinion 18 with the rack 29. 20 The point of intersection of the axis of the worm-shaft 34 and the more or less divergent axis of the shaft coupled thereto is readily established at the center of sphericity of the clutch-facing by setting the ball 57, at the end of the worm-shaft, to 25 the end of said motor-shaft extension 36. It will be understood that the motor-shaft 35 may be itself coupled to the worm-shaft 34 through the medium of the novel coupling-means 39, in which case the floating extension 36 is omitted and the 30 intersection of the axes of shafts 34 and 35 is at the center of sphericity of the clutch-facing 59. The clutch-facing 59 may be shaped otherwise than spherically provided the coupled shafts are 35 in substantially straight alignment.

40 The carriage may be disconnected from the motor at a suitable instant before the carriage strikes the usual arresting portion 98 of the stop 95, so that the carriage has a decelerating momentum when impact of the carriage against 45 said stop-portion occurs. An important advantage resulting from the use of the coupling 39 is that, at said instant of carriage disconnection, the speed of the carriage may be substantially uniform for all extents of return run. It becomes feasible, therefore, that said instant of disconnection may be the same, in relation to the instant of impact, for all lengths of run, and may therefore be finely timed, to the end that the efficacy of said deceleration of momentum to 50 minimize the impact of the carriage against said arresting portion of the stop is materially improved, and obtains for all lengths of carriage-return run. There is not, as heretofore, objectionable variation of the impact according to the 55 length of the carriage-return run.

60 Variations may be resorted to within the scope of the invention, and portions of the improvements may be used without others.

Having thus described my invention, I claim: 65

1. The combination of a reciprocatory type-writer-carriage, a stop for arresting the return of the carriage, a train of mechanism intermittently rotatable to return said carriage, a normally silent motor having a driving shaft disposed in substantially axial alignment end to end with said train, said shaft presenting at its end portion a friction clutch facing, said train having arranged at its end portion a shoe freely 70 pressable against said facing, means for pressing 75

- 5 said shoe against said facing and a centrifugal clutch-releasing device arranged in said train and operative to regulate the pressure of said shoe against said facing with a force inversely proportional to the speed of said train, said facing, shoe, and clutch-releasing device forming a carriage-starting device whereby the carriage is rapidly started upon energization of the motor and the speed of said carriage is, after starting, maintained substantially uniform irrespective of the length of carriage-return run, said facing and shoe forming a spherical joint so that said shoe and facing may also serve as a universal joint between said train and shaft.

10 15 2. The combination of a reciprocatory type-writer-carriage, having a return stop, a train of mechanism intermittently rotatable to return said carriage, a motor having a driving shaft disposed in substantially axial alignment end to end with said train, said shaft presenting at its end portion a friction clutch facing, said train having a shoe freely pressable against said facing, means for pressing said shoe against said facing and a centrifugal clutch-releasing device arranged in said train and adapted to regulate the pressure of said shoe against said facing with a force inversely proportional to the speed of said train, said facing, shoe, and clutch-releasing device forming a carriage-starting device whereby the carriage is rapidly started upon energization of the motor and its momentum is then maintained substantially uniform irrespective of the length of carriage-return run, said clutch facing being spherical in form so that said shoe and facing may also serve as a universal joint between said train and shaft, said shaft and train-ends having ball-and-socket articulation effective to readily establish intersection of the shaft and train axes at the center of the spherical facing.

20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

end of said return run may be accurately controlled to serve to make the typing to begin at a uniform point for all lengths of carriage-return run.

5. 8. In a typewriting machine, the combination of a reciprocating carriage, a stop for the returning carriage, a normally silent motor, and means for energizing said motor to drive said carriage for a return run against said stop, said 10 means including a carriage-starting device between the motor and the carriage, to start the latter rapidly, said carriage-starting device including means automatically responsive to the speed of the carriage, after starting thereof, to 15 slip as the carriage speed increases above the predetermined starting maximum, but to transmit, without slipping, the full torque of the motor at the start of the latter and thereby start the carriage promptly in full step with the motor, 20 without lagging of the carriage with respect to the motor.

9. In a typewriting machine, the combination of a reciprocating carriage, a carriage-returning motor, means for causing the motor to drive said carriage, and a stop against which said motor drives said carriage, said means including a carriage-starting yieldable grip device between the motor and the carriage, effective to start the carriage to full speed without yielding of said 30 grip or lagging of the carriage behind the motor, and arranged to automatically respond to the speed of the carriage, so that the grip yields as the carriage momentum increases above a predetermined maximum, whereby the carriage is 35 promptly started and brought at once to maximum momentum by full motor torque, but said momentum is not exceeded in a long carriage run.

10. In a typewriting machine having a carriage, power means for driving it in a return direction, 40 and a stop for limiting the return movement of the carriage, the combination with a carriage-returning electric motor normally idle, and a carriage-return train mechanism including means interposed therein for normally maintaining the 45 carriage disconnected from said motor, of means for effecting rapid short return movements of the carriage limited by said stop, including a normally-closed clutch connecting the motor to the train, and key-operated means for starting the 50 motor into action and connecting it to the carriage train, said clutch effective to transmit the full driving force of said motor to start said carriage during short runs, said train having means to prevent excessive momentum of the carriage 55 due to motor acceleration during a long run thereof, whereby damage from arresting the carriage by said stop in a long run is prevented, said preventing means including a powerful friction clutch between the motor and the carriage-driving 60 train which is sufficiently effective to maintain the full torque of the electric motor upon the carriage when driving it for short runs, said clutch being releasable by centrifugal force during long runs, to prevent momentum of the carriage from 65 being augmented beyond a predetermined maximum, whereby the blow imparted by the carriage against said stop in terminating a long stroke is about equalized with the blow imparted at a short return stroke, thus permitting increased 70 speed of short return strokes, with consequent increase in the output of the machine.

11. In a typewriting machine, the combination with a carriage, of a mechanism for returning the carriage through either very long or very short 75 runs, a stop for arresting the returning carriage,

said returning mechanism including an electrical motor and a drive-gear train normally disconnected between said motor and said carriage, to permit the usual advance movements of the carriage independently of the motor, said motor being normally idle, and key means for energizing the motor and simultaneously connecting the carriage to the motor through said train and maintaining the connection through a maximum run of the carriage; said carriage-returning train including a normally-closed clutch having a full-power friction element capable of starting the carriage and bringing it to full return speed without lag of the carriage relatively to the motor, for effecting quick minimum runs, and also including 10 centrifugal means for releasing said clutch, to prevent the carriage from gaining excessive momentum during the maximum runs. 15

12. In a typewriting machine, the combination with a carriage, of a mechanism for returning the carriage through either very long or very short runs, a stop for arresting the returning carriage, said returning mechanism including an electrical motor and a drive-gear train normally disconnected between said motor and said carriage, to 20 permit the usual advance movements of the carriage independently of the motor, said motor being normally idle, and key means for energizing the motor and simultaneously connecting the carriage to the motor through said train and 25 maintaining the connection through a maximum run of the carriage; said carriage-returning train including a normally-closed clutch having a full-power friction element capable of starting the carriage and bringing it to full return speed without lag of the carriage relatively to the motor, for 30 effecting quick minimum runs, and also including 35 centrifugal means for releasing said clutch, to prevent the carriage from gaining excessive momentum during the maximum runs, said clutch 40 having driving and driven members, one of said clutch members being a plurality of spring-pressed movable arms, and the other member being a drum, said arms being lined with full-power 45 friction shoes to control said drum without slipping at the start of the motor and carriage, and said arms having centrifugal means for releasing 50 said friction members from said drum to prevent the momentum of the carriage from being augmented beyond a predetermined maximum. 55

13. In a typewriting machine, the combination with a carriage, of a mechanism for returning the carriage through either very long or very short runs, a stop for arresting the returning carriage, said returning mechanism including an electrical 60 motor and a drive-gear train normally disconnected between said motor and said carriage, to permit the usual advance movements of the carriage independently of the motor, said motor being normally idle, key means for energizing the 65 motor and simultaneously connecting the carriage to the motor through said train and maintaining the connection through a maximum run of the carriage; said carriage-returning train including a normally-closed clutch having a full-power friction element capable of starting the carriage and bringing it to full return speed without lag of the carriage relatively to the motor, for effecting 70 quick minimum runs, and also including centrifugal means for releasing said clutch, to prevent the carriage from gaining excessive momentum during the maximum runs, said clutch having driving and driven members, one of said clutch members being a plurality of spring-pressed movable arms, and the other member being a drum, said 75

arms being lined with full-power friction shoes to control said drum without slipping at the start of the motor and carriage, and said arms having centrifugal means for releasing said friction members from said drum to prevent the momentum of the carriage from being augmented beyond a predetermined maximum, a shell upon which said arms are pivoted, and springs anchored upon said shell and bearing against said arms, said shell being adjustable revolubly to regulate the tension of said springs and thereby varying the power of the clutch to accommodate vari-

ations in the length, weight and momentum of the carriage.

14. In a typewriting machine, the combination with a carriage, of an electric motor, and a drive train of mechanism extending from said motor to said carriage and including a set of gearing, a clutch being provided between said motor and said set of gearing, said clutch including complementary friction members having spherical articulation to each other and forming a universal joint, for the purpose set forth. 5 10
